UNITED STATES PATENT OFFICE.

ARTHUR R. MOSLER, OF NEW YORK, N. Y.

SPARK-PLUG.

1,256,719.

Specification of Letters Patent. Patented Feb. 19, 1918.

Application filed September 17, 1915. Serial No. 51,189.

To all whom it may concern:

Be it known that I, ARTHUR R. MOSLER, a citizen of the United States, and resident of the borough of Manhattan, in the city and State of New York, have invented a new and useful Improvement in Spark-Plugs, of which the following is a specification.

My invention relates to an improvement in spark plugs and insulating blocks therefor, with the object in view of providing an insulating block which by reason of its construction and the manner in which it is held in the plug will be less likely to break under the influence of high heat or sudden blows.

It has been customary to make insulating blocks for spark plugs with reduced inner and outer end portions and an enlarged intermediate portion with which the shell and cap of the plug coöperated to form the completed plug. When it was desired to make a block of this character longer, it was customary heretofore to make the reduced inner and outer portions longer and to leave the intermediate enlarged portion of substantially the same length. Long plugs made in this manner were very easily broken by high heat or sudden blows owing to the long overhang of the end portions, the line of fracture usually being near the shoulders between these portions and the enlarged portion. I have discovered that by making the reduced end portion short and of a constant length for all size plugs and increasing the length of the intermediate enlarged portion when a longer plug was desired, I could do away with the long overhang of the end portions and make a much stronger block. Again, I found that by making the intermediate portion of two different diameters, the one remaining constant in length and the other increasing with the length of the plug, I could get a better balanced block which would be less apt to break. The construction of my block is such that there is a greater distance between the bearing points of the block within the plug than there was in plugs heretofore used where the enlarged portion was short as compared with the end portions. This contributes greatly to the strength of the block and it will be seen that the distance between the bearing points is increased as the plug increases in length,

thus making the longest plugs quite as strong as the shorter ones.

A practical embodiment of my invention is represented in the accompanying drawings, in which,

Figure 1 is a longitudinal central section through a spark plug having an insulating block embodying my invention, and

Fig. 2 is a similar view of a longer plug.

The insulating block comprises the reduced inner end portion 2, the reduced outer end portion 3, and the enlarged intermediate portion 4, the formation of which provides the annular shoulders 5 and 6, extending around the periphery of the block. The shell 7 surrounds the inner end portion 2 and the intermediate enlarged portion 4 of the block, which shell is provided with a shoulder 8, between which and the shoulder 5 of the block is inserted a packing ring or gasket 9.

A hollow cap 10 surrounds the insulating block and has a screw-threaded engagement with the outer end of the shell 7, which cap is provided with an annular shoulder 11, between which and the shoulder 6 of the block is inserted a packing ring or gasket 12.

The electrode 13 has the usual screw-threaded engagement with a binding nut 14, adapted to bear on a washer 15 located on the outer end of the block.

The enlarged intermediate portion 4 is so formed as to have its inner part 16 of greater diameter than its outer part 17, the inner part 16 being increased in length when a block for a longer plug is desired, while the outer part 17 is of substantially constant length for all length plugs.

What I claim is:

1. In a spark plug, a hollow shell, a hollow cap, an insulating block having relatively short inner and outer reduced end portions, an enlarged intermediate portion of different diameters, and packing rings between the inner end of the intermediate portion and the shell and between the outer end of the intermediate portion and the cap.

2. In a spark plug, a hollow shell, a hollow cap, an insulating block having relatively short inner and outer reduced end portions, an enlarged intermediate portion of different diameters and packing rings

between that part of the intermediate portion having the greatest diameter and the shell and between that part of the intermediate portion having the smallest diameter 5 and the cap.

3. An insulating block for long spark plugs having short reduced inner and outer end portions and an enlarged intermediate portion of different diameters, the distance

between the bearing shoulders at the inner 10 and outer ends of the enlarged intermediate portion being greater than the length of either the inner or outer end portion.

In testimony, that I claim the foregoing as my invention, I have signed my name, this 15 third day of August, 1915.

ARTHUR R. MOSLER.
